UNITED STATES PATENT OFFICE.

DANIEL T. GLACKIN, OF PHILADELPHIA, PENNSYLVANIA, ASSIGNOR TO UNDERWOOD TYPEWRITER COMPANY, OF NEW YORK, N. Y., A CORPORATION OF DELAWARE.

TYPEWRITING MACHINE.

Application filed December 10, 1919. Serial No. 343,784.

To all whom it may concern:

Be it known that I, DANIEL T. GLACKIN, a citizen of the United States, residing in Philadelphia, in the county of Philadelphia and State of Pennsylvania, have invented 5 certain new and useful Improvements in Typewriting Machines, of which the following is a specification.

This invention relates to the class of typewriting machines illustrated in the patent 10 to Wernery & Smith, No. 1,132,055, dated March 16, 1915, in which a web, which is fan-folded longitudinally, is led through a typewriting machine, so that the outer plies 15 thereof may receive the ink-ribbon impressions, while the inner plies receive carbon duplicates of said impressions.

After the printing on a given section of the web has been completed, the platen is 20 raised to enable the work to be straightened out and drawn forward into engagement with the leading-edge gage, and the carbons to be retracted from the written portions of the web. The advanced portion of the work 25 is then severed by bringing it into engagement with a knife.

The main object of the present invention is to provide simple and efficient means whereby the advantages of using a fan-fold 30 web may be preserved, while at the same time the sheets or plies taken from the machine may be of different lengths, a result which it has been found desirable to attain.

A more particular object of the present invention is to provide means to produce 35 an ink-ribbon copy upon a work-sheet section or form of greater length than the carbon copy or copies and having this increased length at its bottom margin, and to do this 40 at the time of drawing forward all of the straightened-out webs when the platen has been raised or displaced to release the webs to permit such drawing forward of the released and straightened-out webs.

45 In the preferred form of carrying out my invention, provision is made of means for feeding around the platen a fan-folded web and a separate outer sheet or web with suitable carbon sheets interleaved therebetween, 50 and provision may also be made whereby the portion of the work extending around the platen may be released and straightened to enable the work to be drawn forward with reference to the platen. Provision may also 55 be made of a leading-end gage and a grip-

ping device associated therewith, the gage and the gripping device being adjustable together along a gage-carrying bar or guide, and of a second leading-end gage adjustable on the guide and positioned further from 60 the platen than the first-mentioned gage. Preferably, the gripping device is a spring clip effective to grip work drawn between said clip and its support.

After releasing the work, the fan-fold 65 web may be grasped between the first and second fingers, and the single sheet or web between the thumb and first finger of one of the operator's hands, both of the webs being then drawn forward until the fan-fold web is gripped by said spring clip, the fan-fold web then being released from the hand of the operator, and the single web advanced until it engages with the outer gage. The carbons having been retracted, 70 the single sheet is severed by drawing it against a knife, and the fan-fold web is then withdrawn from the gripping device and severed in the same manner, or if desired both webs may be severed at the same time. 75

If desired, the mechanism may be arranged to accommodate, in place of the single web, a plurality of webs or a fan-fold web. Corresponding substitutions may also be made for the fan-fold web. 80

It will be understood the headings on all of the webs or plies will be of the same size, and that the different lengths of severed webs or plies obtained by the mechanism of this invention results from varying the bottom margins. 85

Other features and advantages will hereinafter appear.

In the accompanying drawings,—

Figure 1 is a fragmentary perspective 95 view of a fan-folded typewriting machine of the type disclosed in said Wernery & Smith patent, but modified to carry out the present improvements in one form, the parts being shown in the positions assumed when the 100 platen is lifted to permit release of the work.

Figure 2 is a view illustrating the method 105 of gaging the work, the work having reached the inner gage, with the fan-fold web drawn into position to be gripped by the spring clip.

Figure 3 is a view similar to Figure 2, but showing the operation of gaging the single web after the fan-fold web has been engaged by the spring clip. 110

Figure 4 is a perspective view, showing in detail the guide or gage support, the spring clip and the leading-end gage with which the spring clip is associated and which holds said spring clip on the gage support.

In addition to the fan-fold web 9, a single web 10 is used, and both webs with interleaved carbons 11 are led around the platen 12 in such relationship to each other that the ink-ribbon copy will be made upon the single web 10 and carbon copies will be made upon the plies of the fan-fold web 9. The sub-carriage 13, which is the same as that employed in said Wernery & Smith patent for retracting carbons 11 between the plies of the fan-fold web when desired, is provided with an extra carbon which lies between the fan-fold web 9 and the single web and will be shifted with the carbons interleaved in the fan-fold web.

The platen 12 of the machine herein illustrated, like that shown in the Wernery & Smith patent, is journaled by an axle 14 in the swing frame comprising ends 15, which are journaled on a shaft 16, supported in a main platen-frame 16^a. The platen axle is geared to the line-space wheel 17 by pinion 18 fast on the axle 14 and meshing with a pinion 19 fast on the shaft 16, the latter pinion also meshing with a pinion 20 which is fast to the shaft 21 of the line-space wheel 17. The platen 12 is held against the feed-rolls 22 and 23 by means of a handle 24 on the swing frame caught by the usual pivoted hook 25. The typist may swing the swing frame up by pushing the hook 25 rearwardly to release the handle and then drawing on the handle, with the result that the platen will swing up until the webs 9 and 10 drawn along the sub-carriage 13 may be stretched straight forwardly under the platen.

Before insertion of the fan-fold web 9 and the single web 10, the feed-rolls 22 and 23 may be released by the usual feed-roll release mechanism, illustrated more fully in said patent to Wernery & Smith, the connection between the handle 24 and the hook or latch 25 being such as to support the platen when the feed-rolls are released. The webs 9 and 10 may then be inserted over the usual rear paper-table 25^a and guided around beneath the platen 12 by the usual curved paper-table 25^b, and led between the usual web-severing knife 26 and the platen, the leading end of the work then resting on a web-supporting and guiding shelf 27, which may be fixedly secured to the ends 15 of the swing frame. A bar or guide 28 forms an extension of the shelf 27, to swing forwardly and downwardly therewith to a substantially horizontal position, and is provided with an adjustable end gage 29, which may be secured to the bar 28 at any desired point by means of a clamping screw 30.

In addition to end gage 29, provision is made of a second end gage 31 held in adjusted position on the bar 28 by means of a clamping screw 32. End gage 31 comprises a body portion 33 and portions 34 preferably perpendicular thereto, each of said end portions 34 being provided with an opening 35 of sufficient size to receive the bar 28 and also a leaf spring 36 placed thereon. The leaf spring 36 may be connected with said gage 31 to move therewith by means of lugs 37 and 38 spaced apart so as to engage portions 34 of the end gage 31 on their outer sides. The end gage 31 and leaf spring 36 may be assembled on bar 28 by inserting the end of leaf spring 36 in openings 35, Figure 4, and moving said spring into position to present said lugs 37 and 38 in engagement with the outer sides of portions 34 of end gage 31. The bar 28 may then be inserted in openings 35, and the leaf spring 36 thus secured, by means of the screw 32, to end gage 31 to move therewith. The leaf spring 36 is arched outwardly from bar 28 in the proper direction to receive beneath it work advanced to end gage 31, and will grip and hold work drawn between it and the bar 28.

When the typewriting or printing on one bill or piece of work has been completed, the leading ends of the webs 9 and 10 will usually lie in an intermediate position between said end gage 31 and the printing line.

The handle 24 may now be released by lifting the latch 25 and then swung forward to lift the platen from its normal depressed web-holding printing position to its raised web-releasing position, and concomitantly to swing the paper-shelf 27 and gage-carrying guide-bar 28 from the normally upstanding to the forward substantially horizontal position, the two positions of the platen 12 and guide-bar 28 being indicated diagrammatically in Figure 2. The paper-shelf or shield 27 and the gage-carrying bar 28 will now be substantially horizontal and approximately in line with the portions of the webs behind the platen. The webs will thus be released by the platen 12 and may be straightened to enable the same to be pulled forward and gaged, being thereby repositioned relatively to each other and to the retracted carbon sheets 11.

When the handle 24 is swung forwardly, the leading ends of the webs are grasped by the operator and drawn forwardly. In view of the fact that the webs are to be drawn across the knife 26 to be severed, it will be necessary to retract the carbons, which may be effected by any suitable means, such, for example, as that shown in said Wernery & Smith patent. In order to carry out the purpose of the present invention, it is necessary to pull forward the fan-fold web to engage end gage 31, and in so doing to draw

it under leaf spring 36, thereby effecting a clamping or gripping of the fan-fold web in this position. The single web 10 will then be drawn farther forward until it engages the end gage 29. It should be noted that the portion of end gage 29, with which the web 10 is brought into engagement, projects farther from bar 28 than either end gage 31 or leaf spring 36, and that work 10 may therefore be drawn forward into engagement with end gage 29 without interference by either end gage 31 or leaf spring 36.

An important advantage of this invention 15 consists in the possibility of manipulating the webs, for the purpose described, by the use of one hand only. This may be done by grasping the single web 10 between the thumb and forefinger, and the fan-fold web 20 9 between the forefinger and the second finger, drawing both webs forward to bring the fan-fold web between the leaf spring 36 and the bar 28 to be gripped and held thereby, and then releasing the fan-fold web from 25 the fingers and drawing the single web to the position shown in Figure 3. It is to be noted that the manner of manipulating the webs provided for by the present invention, results in producing a wider bottom margin 30 of any desired extent on the ink-ribbon copy at the single operation of drawing forward and gaging the released webs, which are stretched substantially straight forward beneath the raised or displaced platen 12. 35 Also it is to be noted as of importance that, when the webs 9 and 10 are thus drawn forward and gaged against the respective gages 31 and 29, these webs are thereby positioned relatively to the retracted carbons 11, which 40 have been moved back by the carbon carriage or sub-carriage 13 in the usual way; and also when the webs 9 and 10 are thus drawn forward and separately gaged they are brought to the correct position for severing 45 or tearing off the typed set of work-sheets by the knife 26 after the restoring of the platen 12 to its normal or typing position, while at the same time the next succeeding set of work-sheet sections or forms 50 on the webs 9 and 10 will be brought to the correct position for the typing to proceed thereon.

The platen-displacement or swing frame 55 may then be restored to its normal position, which will bring the platen from the upper position shown in Figure 2 to the lower position there indicated by the showing of the gage-carrying bar 28 in broken lines. The single web may then be severed by drawing 60 it over knife 26, and the fan-fold web may then be withdrawn from the gripping device, of which leaf spring 36 forms a part, and drawn across the knife 26, or if desired both webs 9 and 10 may be severed at the 65 same time. The operator may then proceed

to typewrite or print another piece of work, the work-sheet sections or forms of which have been brought forward to the typing position by the gaging of the leading edges of the previously typed work-sheet sections 70 or forms, as hereinbefore described.

Variations may be resorted to within the scope of the invention, and portions of the improvements may be used without others.

Having thus described my invention, I 75 claim:

1. In a typewriting machine, a platen, a carriage therefor, and means for collating work-webs comprising a narrow bar or staff carried by the carriage at the delivery side 80 of the platen, a leading-edge gage upon the bar for gaging the inner web, a flaring guide co-operating with the gage for intercepting the leading edge of the inner web, and a second gage on the bar at a measured distance beyond the first gage and of greater height than the first gage for gaging the outer web.

2. In a typewriting machine of the continuous billing or fan-fold type, in combination, a revoluble platen, a displaceable swing-frame in which the platen is mounted to swing forwardly to provide for the straightening out and drawing forward of work-webs, an adjustable inner leading-edge gage 90 at the delivery side of the platen and carried by the swing-frame for gaging the leading edge of the inner one of said straightened-out webs, a sheet-gripping device having a flaring mouth carried by said gage and constructed and arranged to intercept the leading edge of the inner web as it is drawn forward, to guide the leading edge of said web into engagement with said gage and to yieldingly grip the leading margin of the 100 web in this gaged position, and an adjustable second leading-edge gage beyond the first for gaging longer work-sheet sections or forms on the outer one of said webs.

3. In a typewriting machine, a revoluble 110 platen, a gage-carrying bar at the delivery side of the platen, a leading-edge gage carried by and adjustable along said bar for gaging the leading edge of a work-web, and a sheet-gripping device carried by said 115 gage and constructed and arranged to intercept the leading edge of the work-web as it is drawn forward, to guide the leading edge of said web into engagement with said gage, and to yieldingly grip the leading margin 120 of said web to retain it in its gaged position.

4. In a typewriting machine of the continuous billing or fan-fold type, in combination, a revoluble platen, means to guide 125 superposed webs to and around beneath the platen, means for displacing the platen to provide for the straightening out and drawing forward of said webs, means for separately gaging the leading ends of the webs 130

while in straightened condition, comprising a gage-carrying bar swingable forwardly from an upstanding to a substantially horizontal position at the displacement of 5 the platen, said bar being narrow enough to permit the operator to grip the leading margins of the work-webs with his hand located in intersecting relation to the plane of the bar, to draw the work-webs forward 10 for gaging, an inner leading-edge gage on said bar for gaging the leading edge of an inner one of said webs when drawn forward, and a second leading-edge gage on said bar outward from said inner leading-edge gage 15 and at a fixed predetermined distance therefrom for separately gaging the leading edge of another of said webs outward from said inner first-gaged web, and a web-severing knife displaceable with the platen and adjacent the front thereof for severing said separately-gaged webs at a single operation.

5. In a typewriting machine of the continuous billing or fan-fold type, in combination, a revoluble platen, means to guide 20 superposed webs to and around beneath the platen, means for displacing the platen to provide for the straightening out and drawing forward of said webs, a gage-carrying bar at the delivery side of the platen and 25 swingable forwardly from an upstanding to a substantially horizontal position at the displacement of the platen, an inner leading-edge gage projecting forwardly from and 30 adjustably fixed upon said bar for gaging the leading edge of the inner one of said webs when drawn forward, a sheet-gripping device carried by said gage having a flaring 35 mouth opening toward the platen, to receive

and grip said inner web as it is drawn forward against the leading-edge gage, and a second leading-edge gage, of greater height 40 than the first, projecting forwardly from and adjustable along said bar outward from said inner leading-edge gage for separately gaging the leading edge of another of said webs. 45

6. In a typewriting machine, in combination, a revoluble platen, a guide extending from the delivery side of said platen, an end gage embracing said guide, a clamping screw mounted in said end gage to press 50 against said guide, to draw the opposite portion of said gage against said guide, and a leaf spring inserted between the guide and the portion of said gage opposite said screw, 55 said leaf spring being effective to hold in position on said guide, work drawn against said end gage.

7. In a typewriting machine, in combination, a guide along which work may be drawn, a leading-end gage having a body 60 portion and two ears offset therefrom, provided with openings to receive said guide, a leaf spring inserted in said openings opposite the body portion of said gage, lugs 65 projecting from said leaf spring, so as to engage said ears on opposite sides, to prevent movement of said leaf spring other than with said end gage, and means to clamp the end gage and the leaf spring in adjusted 70 position on said guide.

DANIEL T. GLACKIN.
